UNITED STATES PATENT OFFICE.

JOHN W. TAYLOR, OF YORK, PENNSYLVANIA, ASSIGNOR TO THE TAYLOR MANUFACTURING COMPANY, OF LYNCHBURG, VIRGINIA.

TURBINE WATER-WHEEL.

SPECIFICATION forming part of Letters Patent No. 651,731, dated June 12, 1900.

Application filed September 24, 1898. Serial No. 691,809. (No model.)

To all whom it may concern:

Be it known that I, JOHN W. TAYLOR, a citizen of the United States, and a resident of York, in the county of York and State of Pennsylvania, have made certain new and useful Improvements in Turbine Water-Wheels, of which the following is a specification.

The object of my invention is to improve the construction of that class of turbines which receive the water upon the upper part of the buckets through stationary guides or chutes surrounding the wheel proper, the admission of water being controlled by means of an annular or cylindrical gate, which is adjustable in such manner as to open or close the water inlets or chutes at the top.

The several features of construction, arrangement, and combination of parts embodying my invention are hereinafter set forth, and illustrated in the accompanying drawings, (two sheets,) in which—

Figure 1 is a side elevation of my improved wheel, the gate being shown lowered, as required for free admission of water. Fig. 2 is a central vertical section of the wheel proper. Fig. 3 is a horizontal section on line 3 3, Fig. 2. Fig. 4 is a horizontal section on the line 4 4, Fig. 2. Fig. 5 is a plan view of the cylindrical gate. Fig. 6 is a side view of the wheel proper or runner.

The parts comprising the wheel-casing are indicated by lower-case letters, and the movable parts are indicated by numerals, for convenience of distinction. The upper portion 35 of the wheel-casing comprises the horizontal top or cover *a*, the guide or chute frame *b*, which is circular and arranged vertically; the central draft-tube *c*, upon which said guide-frame *b* is supported; the supporting 40 base-flange *d*, and the flaring lower draft-tube *e*. The latter is bolted or riveted to the lower or pendent flange of the ring *d*. The central cylindrical draft-tube *c* is supported upon the inner horizontal flange of the base-ring *d* and bolted to the vertical flange of the same. (See Fig. 2.) The exterior horizontal flange of the base-ring *d*, which rests upon the floor of the flume, as indicated by dotted lines in Fig. 1, and is suitably bolted thereto. 45 The upper portion of the central draft-tube *c* (see Fig. 2) is rabbeted or grooved to adapt

it to receive the base of the guide-frame *b*, which is bolted thereto. Within the lower or flaring draft-tube *e* is arranged a horizontal skeleton frame or "spider" *f*, which is 55 bolted to the sides of said tube, as shown in Fig. 2. Said spider is provided centrally with a polygonal socket adapted to receive the corresponding shank of a removable step-block *l*, whose upper end is conical and fits 60 in a corresponding recess in the rotary shoe *2*, in which the wheel-shaft *3* is stepped. The lower end of said shaft is polygonal and fits in a corresponding socket in the aforesaid shoe *2*. The shaft is guided and adapted for 65 adjustment in vertical position by means of blocks *4* and set-screws *5*, connected with the box *g*, forming an attachment of the top *a* of the wheel-casing. A packing *6*, composed of fibrous material or leather, is arranged around 70 the shaft *3* in the upper portion of said box *g* for the purpose of preventing influx of air to the runner of the turbine. Said runner *7* is provided with a tapered hub *8*, which is 75 suitably keyed upon the shaft *3*. Surrounding the lower portion of the buckets *9* is a thick band *10*, whose upper edge is rounded or beveled, as shown in Fig. 2, and works in frictional contact with a correspondingly-beveled flange *h*, that projects inwardly from the 80 top of the central draft-tube *c* and is constructed integrally therewith. By this means the escape of water between the buckets and the lower edge of the guide-frame and top of the draft-tube is avoided, and the whole power 85 or force of the water-current is therefore expended upon the buckets.

My improved gate 12, by which the influx of water to the wheel proper is controlled, is made cylindrical in form and adapted to surround the guide-frame *b* and central draft-tube *c*, as shown. Said gate is provided at its lower edge interiorly with an inwardly-projecting flange *i*, which works in sliding contact with the draft-tube *c*. The upper 95 edge of the latter is also provided with a corresponding flange *i*, which extends outwardly and works in sliding contact with the inner side of the gate 12. The upper edge of the gate has also an inwardly-projecting flange 100 *l*, which works in contact with the edges of the bars composing the circular chute-box *b*.

By this arrangement close joints are formed, friction is reduced to a minimum, and the upper flange 15 cuts or shears off weeds, plant-stalks, and other trash that may lodge 5 against the chute-bars. A series of lips or flanges 16 is bolted to and projects from the gate between the chute-bars; but this feature is unimportant.

It will be seen that my improved gate is 10 adapted to open downward and close upward, so that water is admitted at the top of the wheel proper, and thereby produces the greatest effect practicable before being discharged from the wheel into the draft-tube *c*. I propose to employ any suitable means for raising and lowering the gate; but in this instance I show rods 17 for this purpose, the same being connected to rack-bars 18, whose teeth mesh with pinions 19 upon a transverse 15 shaft 20. Rotation is imparted to said shaft by means of beveled gearing 21, operated from any suitable source of power. I counterbalance the gate and the rods and rack connected therewith by means of a weight 22, 20 (see Fig. 1,) which is supported by cord or wire rope running over a pulley 23, that is keyed upon the said shaft 20. By this means the gate may be adjusted for opening or closing with great ease and rapidity.

25 The hoisting-rods 17 work in guides 24, fixed on the top *a* of the wheel-casing and are connected with the two parts of the gate at the meeting edges of the latter. Their lower ends are flattened, as shown in Figs. 2 and 4. The gate 12 is constructed in two 30 semicircular parts, and such flattened portions of the rods are of such width as to span

the joint formed by the adjacent or meeting edges of such semicircular parts, and, being bolted to the latter, they connect them so 40 that they form a rigid cylinder.

What I claim is—

1. In a turbine water-wheel, the combination, with the runner and its surrounding chute-box, composed of thin bars arranged 45 circularly, and the cylindrical draft-tube *c*, supporting said chute-box, and having an exterior flange *i*, of the annular slidable gate, having the lower internal flange 13, working in contact with said tube, and the upper 50 flange 15 working in contact with the chute-box, the tube-flange *i* being in contact with the body of the gate, as shown and described.

2. In a turbine water-wheel, the combination, with the wheel proper, of an annular gate made of separable parts, and adjusting-rods connected with said parts at their joints, substantially as specified.

3. In a turbine water-wheel, the combination with the wheel and wheel-casing having a guide or chute frame as specified, of the cylindrical gate formed with two semicircular parts and adjusting-rods arranged on opposite sides of the wheel and having their 60 lower ends flattened to span the joint between such semicircular parts, to which they are bolted, thereby connecting them rigidly as shown and described.

JOHN W. TAYLOR.
